GEORGE M. ARAGG, OF LAWRENCE, MASSACHUSETTS.

STOP-MOTION.

1,374,417.

Specification of Letters Patent. Patented Apr. 12, 1921.

Application filed May 7, 1919. Serial No. 295,302.

To all whom it may concern:

Be it known that I, GEORGE M. ARAGG, a citizen of Turkey, residing at Lawrence, in the county of Essex and State of Massachusetts, have invented certain new and useful Improvements in Stop-Motions, of which the following is a specification.

This invention relates to stop-motions for spinning frames and is particularly an improvement on the device shown in patent to me of January 18, 1916, No. 1,168,457.

On a cap spinning frame, where such device is especially useful, there are usually one hundred spindles on each side, and one spinner takes care of three sides or three hundred spindles. Empty bobbins are placed on the spindles on one side and all are started together and are run until full, when all are stopped together. Thereby all have practically the same amount of yarn, except those whose ends have broken.

There must be sufficient clearance between the delivery rolls and the cap and bobbin to allow for doffing, but the guide eye for the yarn must be directly over the axis of the cap and bobbin and fairly near the top thereof to prevent the yarn from stretching and breaking. With my device, I prefer that the guide eye should be carried by the rocking member, which must therefore be arranged so that it can be lifted enough for doffing. Its back end or tail must be capable of sidewise motion between the vibrator and the flexible member.

When piecing, the tail of the rocking member should be held up away from the vibrator, and it is desirable that it should be held up as soon as the stop-motion has acted. It is desirable that all the tails should be held up when the frame is stopped or slowed down to prevent the vibrator from acting and thus breaking the ends, or, that provision should be made so that the vibrator should stop just before the delivery rolls and spindles stop.

When a strand of roving breaks, it is desirable that delivery of its end should cease and that an unskilled operator should be able to rapidly and easily start and piece such ends and reset the stop-motion without exercising much care.

It is my purpose to provide means whereby when an end does break, as is most common, between the delivery rolls and the bobbin, the stop-motion will act automatically to firmly and gently hold the roving, but

not to cut it, at the back rolls so that it will break just back of the delivery rolls, and so that the operator can, with one movement, start delivery, then piece the ends, and by another movement reset the stop-motion for the next break, or, as will be explained, so that he can ignore the broken end until the frame is doffed.

Especially on fine work or when there is much vibration to the mill or machinery, and in any case for the best operation of such frames, the rocking member should not chatter nor rock beyond certain limits until an end breaks, or it will be struck by the vibrator and the stop-motion mechanism will act to unnecessarily stop delivery, but it should be certain to tip when an end does break.

To be useful, a stop-motion must be certain and positive in its action, and of such construction that the operator can reset it with ease and certainty.

I therefore make my rocking members of such form that their action will be steady and positive, that they will not interfere with the doffing, and I make the lifting plate of such form that the roving will break just behind the front rolls.

In the drawings, Figure 1 is a diagrammatic side elevation of my device in place on a cap spinning frame of well known type, the parts being shown in the running position and the rocking member being shown as one-piece. Fig. 2 is a side elevation in detail showing a two-part rocking member, with the carriage for setting, vibrator and other parts in the position which they assume after an end is broken, the tail of the rocking member has dropped and has been pushed over by the vibrator, releasing the flexible member and the leaf spring. Fig. 3 is a plan view of Fig. 2. Fig. 4 is a side elevation of the carriage and adjoining parts in the position assumed when the carriage is pulled forward for setting. Fig. 5 is a plan view of Fig. 4. Fig. 6 is a front elevation of another form of guide eye, and Fig. 7 is a side elevation of Fig. 6. Fig. 8 is a side elevation of another form of guide eye. Fig. 9 is a detail in perspective of a slightly modified form of padded roll separating means. Fig. 10 is a detail showing the leaf spring retaining hook from the front.

A represents the frame of a spinning machine.

B represents the cap, C the bobbin, F and G the back drawing rolls, H the top carrier rolls and M the bottom carrier rolls, K and L the front drawing rolls all substantially of usual construction, and N represents the roving from the roving spool.

The bottom back drawing roll G is positively driven by any usual means as is also the bottom front drawing roll L. The top front drawing roll K may be of any usual construction. For each strand or plurality of strands of roving which are to be twisted into a single end, I use a separate top back drawing roll F. Each is carried by a hanger 20 slidable through a hanger frame 21. Through each hanger 20 passes a hanger pin 22 into frame 21, the hanger being slidable thereon. Around pin 22 between hanger 20 and an adjusting nut 23 is a back roll spring 24 which tends to keep the top back drawing roll F in engagement with the bottom back drawing roll G, whereby the yarn or roving N will be drawn in and delivered in the usual manner.

25 Fixed to any suitable rail or bar 30 fixed to the frame of the machine are one or more L shaped plates 31, each with a horizontal shelf 32. For each back top roll F, I provide a lifting plate 33 pivoted to 31 with its free end at a point between rolls F and G not touching either. The roving N passes between the end 34 of this lifting plate and top roll F.

A compression spring 35 between lifting plate 33 and shelf 32 would force plate 33 upward into engagement with roll F were it not for restraining means which I will now describe. On a cross bar P extending across the frame of the machine substantially below each lifting plate 33 is fixed a stretcher plate 40 with a slot 41 and a shoulder 42 which projects thereinto. A flexible member 44 which may be a chain or wire rope is fastened at one end to the bottom of lifting plate 33 and extends downward therefrom, preferably through lifting plate spring 35, and through shelf 32 downward through slot 41 thence at a substantially sharp angle backward to a bar or shaft 9 attached to the frame where the other end is fastened. Transversely of the machine approximate to and preferably under the stretcher plates 40, I place a vibrator rod 50 which carries fingers 51 which extend upward and preferably partly over each stretcher plate 40 in proximity to the member 44 and under the end of a rocking member. This vibrator 50 is moved back and forth continually by any suitable means.

60 The shoulder 42 is at the front of the slot 41 and on the side adjoining the vibrator finger. As the back end of flexible member 44 is fixed, it is manifest that if it is pulled forward and caught over shoulder 42, it will pull downward lifting plate 33

against spring 35 and will hold it in that position until member 44 is pushed off from the shoulder 42 into the main slot 41.

As the lifting plate spring 35 is much stronger than the top roll spring 24, if not held down, the lifting plate will lift the top roll to the position shown in the dotted lines wherein it is separated from the bottom roll and moreover the roving end will be pinched between the end 34 of the lifting plate and the surface of the top roll F and so held that the pull of the front rolls K and L will break it between the front and back rolls.

As shown in Fig. 1, I may use a one-piece rocking member O pivoted to the frame at 61 having a light front part 14 terminating in the thread guide at 19 between the front delivery rolls and the cap of the bobbin, and a heavier back part 10 which extends back beyond the flexible member 44 and the shoulder 42. The back part 10 is so placed with reference to the vibrator finger 51 that, if the front part 14 is not held down, the back part 10 by its own weight 90 will drop in front of 51 and, as the pivot for my rocking member is so made that it can rock vertically and the rear part can also move horizontally, when struck thereby, it will be moved over the shoulder 42 95 pushing member 44 off therefrom in a manner similar to that described in my aforesaid patent. This rocking member is so placed and balanced that the action of the roving passing down from the front rolls 100 to the bobbin will depress the front end and raise the back end above the path of fingers 51 as shown clearly in Fig. 1.

I find that by forming the thread guide so that the roving N will be given a double 105 bend out of a straight course, the tendency of the rocking member to chatter is overcome, and I consequently so form my guide eye as to depress the front end of the rocking member while the roving is being wound 110 or spun on the bobbin and to keep it steadily depressed.

As shown in Fig. 2, I prefer, however, to enlarge the back end of the front part 14 at 12 and to form a slot therein to receive 115 the tail 13 forming the front end of back part 10 which is so pivoted at 11 that it can move horizontally and can be raised independently of the front part. Normally, however, they are in alinement and if either 120 is depressed the other is elevated. I prefer to bend upward the back end 64 of the back part 10 for a reason to be explained.

As described in my patent above mentioned, when the parts are set with the flexible member 44 pulled forward and caught on shoulder 42, the lifting plate is clear of the top and bottom back rolls, the guide eye and free end of the rocking member is depressed by the pull of the roving, the back 130

part 10 is raised above the vibrator 51 and the machine keeps on running until the end breaks. When this happens, the weight of the back end 10 depresses it until it falls in front of the vibrator 51, as shown by the dotted lines in Fig. 1, when it is stopped thereby and is pushed over, releasing 44 from 42 and the lifting plate whereby the top back roll is raised and the roving held 10 at that point.

It is very desirable that the roving should be pinched but not cut at the back rolls so that it will break just behind the front rolls whereby, when the frame is again started, 15 it will automatically feed itself through the front rolls, and to accomplish this I provide a pad 36, preferably of leather or similar yielding material, on the front edge of the lifting plate where it comes in contact with 20 the top back roll.

As the lifting plate must be moved back and forth according to the length of the fiber operated on, I also prefer to form in the bottom shelf 32 thereof an extension 25 with a relatively long curved bearing trumpet 37 whereby the flexible member, which is shown as a wire 44, can easily run through without turning any sharp corner.

My attachment is for the same purpose as 30 the aforesaid patent but, as the usefulness of such stop-motions is not only for saving waste and saving labor but for such automatic action on all kinds of stock that little skill or intelligence is required from the 35 operator, I have devised the improvements described herein.

A simple straight guide eye will work satisfactorily with coarse yarns and where there is little vibration, but with fine yarns, 40 or where there is vibration, there is a tendency for the rocking member 10 to chatter or shake out of position, thus stopping the delivery rolls when not desired. It is for this reason that I introduce the double bend 45 in the guide attached to the front part of the rocking member.

When a strand of roving breaks, it is usually between the bobbin and the delivery rolls, and for convenience in piecing up the 50 broken end it is desirable that not only should the back top roll be lifted, but that roving should be automatically broken as nearly behind the front delivery rolls as possible. For this reason I introduced the 55 padded edge 36 on the lifting plate 33. This padded edge holds the stock at that point but does not cut it and, as the distance between the front and back rolls is adjusted to be slightly more than the length of the 60 fiber, the roving is gently pulled apart between the front rolls and the forward carrier rolls just behind the nip of the front rolls.

When an end breaks, the drag on the 65 guide eye ceases, and the weight of the back

part of the rocking member causes it to drop in front of the vibrator whereby the flexible member is released. I find it desirable to immediately return the parts to their running position before the broken end is 70 pieced. For this purpose I use a hook 91 fixed to the stretcher plate 40 outside of the shoulder 42 and to pivot a leaf spring 90 on a pivot 92 at the back of the stretcher plate in such manner that it can move horizontally from side to side under the carriage 71 and so that its front edge can be 75 caught under hook 91.

In this leaf spring 90 I provide a forward and back slot 93 which is relatively narrow 80 and which, in one position partly registers with the slot 41 in the stretcher plate, and the forward part of which in another position registers with the shoulder 42. This slot 93 is relatively narrow and through it 85 extends the flexible member 44. I may provide an extension, shown at 94, which is integral with the front of the spring extending under the back part 10 of the rocking member in whatever position the spring 90 may be.

The bottom of the carriage is so cut away that this spring can move horizontally from right to left and the spring is so positioned that, when the flexible member rests against 95 shoulder 42, one edge of it will be under or over hook 91.

The front edge 72 of carriage 71 may be slanted from front to back toward the shoulder 42 and hook 91, or the parts may be so positioned that the two ends of the flexible member 44 will be approximately in a plane 100 extending back of hook 91. In either case, when carriage 71 is pulled forward, as shown in Fig. 4, the flexible member is 105 forced over on to shoulder 42, and the front side of spring 90 is forced down and over so as to be caught under hook 91. When carriage 71 is pushed back spring 90 is therefore 110 caught and held until an end breaks, allowing 10 to drop in front of the vibrator which pushes it over, also pushing over flexible member 44 from the shoulder 42, and this carries with it spring 90 which is released from 91, upon which its front end 115 94 springs up, lifting tail 10 up out of the way of the vibrator and allowing the guide eye to drop back into the running position whereby the broken end can readily be pieced. This arrangement prevents breakage and clears the back part of the rocking member from being struck by the vibrator 120 until such time as the operator gets around to piecing the ends.

When the operator is ready to piece the 125 end, it is necessary only to pull forward carriage 71, which has a raised part 74 under 10 of such height that it holds up that part 10 when the leaf spring 90 is depressed. The carriage is pulled forward by means 130

of handle 70, thus bringing back all parts to the running position, upon which the back rolls start delivery and the broken end is automatically fed through the front rolls 5 and pieced by the operator.

When so pieced, the operator should push back handle 70 and carriage 71 to allow the trigger mechanism to work but, if he fails so to do, the frame continues to run as if 10 my attachment were not there.

I prefer to make my rocking member O in two parts pivoted so that the back is heavier, as the space in such machines must necessarily be limited and, in removing the 15 cap and spindle, it is necessary to lift the front part for clearance.

I also prefer to use a lifting bar, such as 8, running the length of the frame under the back parts of the rocking members with 20 suitable devices, permitting it to be lifted just before the frame as a whole is to be stopped to prevent the back parts dropping as the speed decreases, unnecessarily breaking ends.

25 I may use the form of guide eye shown in Figs. 6 and 7, wherein a well known form of guide eye so slants at an angle with the vertical instead of slanting horizontally, that it gives a double bend to the roving.

30 I prefer the form of thread guide shown in Figs. 1 and 2, wherein the guide eye proper 19 is of the usual form, but at 17 a vertical arm extends from the front part 14 and is bent over at 18 so that the double 35 bend is made between 18 and 19.

In Fig. 8, I show still another form of 40 guide eye, wherein the front part 130 of the rocking member O is bent around horizontally at 131 to form a spiral guide eye and then extends upward and forward at 132, being again bent at 133 to give the roving end the double bend desired.

If there is no stop-motion, the roving winds up on one of the front rolls which 45 continues to run, forming what is known as lap waste or else the broken end runs on to an adjoining bobbin, thus making double spinning and imperfect yarn.

In some mills, the broken ends are pieced 50 after the lap waste has been removed, while in other mills the roving is broken by the operator behind the back rolls.

Where the first method is used, more production is obtained but there is likely to be 55 a flaw in the yarn where it is pieced. Where the second method is used, that particular bobbin is put out of action, and no more yarn is spun on it until it is doffed, but what yarn has been spun is more perfect.

60 In either case, the operator must be constantly on the alert and must be continually piecing ends or breaking the yarn, behind the back rolls. A serious objection to breaking the yarn behind the back rolls is that

after the frame is doffed, in order to start 65 each broken end, its top back roll must be lifted and all its top carrier rolls must be removed so that the roving can be passed through to the front rolls.

As the doffing and starting up of a frame 70 takes much time, it is very necessary that the method and machine should be such that this can be quickly done. To accomplish this I make the front part of my rocking members pivotal or flexible and I arrange 75 my lifting plate so that when an end breaks, it will not only lift the back top roll instantly but will hold the roving gently but firmly, while the front rolls pull it apart at a point between themselves and the front 80 carrier rolls.

When broken at this particular point, it is not necessary to pass the roving again through the back roll, as when the operator starts the machine by dropping the back roll 85 into place, the roving will be fed instantly and automatically to the front roll.

With my device, whichever method is used, either piecing the broken ends or breaking them behind the back rolls, lap 90 waste is prevented. When production is required the operator can piece the ends, but when unpieced yarn is required, it is not necessary to break the ends behind the back rolls as when the top back roll is lifted, delivery is stopped and the roving is gently held and broken behind the front rolls. One operator can therefore take care of a very large number of machines while they are 95 running. In fact, the necessity for spinners 100 is done away with altogether except to generally supervise perhaps ten or twenty machines.

The only operators required are the doffers.

105 Steadiness in the rocking members, positive and certain action by the lifting plate trigger mechanism and the gentle padded grip of the lifting plate or roll separating means, are all necessary for good operation.

110 It is clear that the lifting plate spring 35 might be replaced by a weight, and I will call it and the lifting plate "padded means adapted to separate the back drawing rolls."

I will call the flexible means with the 115 stretcher plate and connections "means for holding such padded means out of action", and I will call the vibrator "power driven means for releasing the last named means."

I claim:

1. In a spinning frame having back drawing rolls, front drawing rolls and a bobbin, the combination of a two-part rocking member, the front part terminating in a thread guide over the bobbin between the front drawing rolls and the bobbin so arranged that the roving will be given a double bend in passing therethrough, and being pivoted to 125

- rock vertically on the frame, and the rear part being pivoted to the front member so as to rock vertically independent thereof and to swing horizontally, both within the limits 5 of suitable stops, with a vibrator, a stretcher plate in which is a slot having a shoulder, a hook carried by such stretcher plate, a spring having a slot in operative relation with the slot and shoulder of the stretcher plate so 10 pivoted to the back of the stretcher plate that it can be caught under the hook with its front end under the rear part of the rocking member, and a flexible member which passes through both slots, together with a 15 carriage adapted to slide under the back part of the rocking member and over the spring to set the flexible member on the shoulder of the stretcher plate and to depress and catch the spring under the hook by the same 20 movement, and padded means held out of action by the flexible member for separating the back drawing rolls, and for holding the roving thereat whereby it is broken behind and close to the front rolls.
- 25 2. In a spinning frame having back drawing rolls, front drawing rolls and a bobbin, the combination of a two-part rocking member, the front part terminating in a thread guide over the bobbin between the front 30 drawing rolls and the bobbin so arranged that the roving will be given a double bend in passing therethrough, and being pivoted to rock vertically on the frame, and the rear part being pivoted to the front member so 35 as to rock vertically independent thereof and to swing horizontally, both within the limits of suitable stops, with a vibrator, a stretcher plate in which is a slot having a shoulder, a hook carried by such stretcher 40 plate, a spring having a slot in operative relation with the slot and shoulder of the stretcher plate so pivoted to the back of the stretcher plate that it can be caught under the hook with its front end under the rear 45 part of the rocking member, and a flexible member which passes through both slots, and padded means held out of action by the flexible member for separating the back drawing rolls and for holding the roving 50 thereat whereby it is broken behind and close to the front rolls.
3. In a spinning frame having back drawing rolls, front drawing rolls and a bobbin, the combination of a rocking member, the 55 front part terminating in a thread guide over the bobbin between the front drawing rolls and the bobbin so arranged that the roving will be given a double bend in passing therethrough, and being pivoted to rock 60 vertically on the frame, and to swing horizontally, with a vibrator, a stretcher plate in which is a slot having a shoulder, and a flexible member which passes through both 65 slots, and padded means held out of action by the flexible member for separating the back drawing rolls and for holding the roving thereat whereby it is broken behind and close to the front rolls.
4. In a spinning frame having front drawing rolls, a bobbin, and separable back drawing rolls, the combination of a rocking member, the front part terminating in a thread guide over the bobbin between the front drawing rolls and the bobbin pivoted to rock on the frame, with padded means 70 adapted to separate the back drawing rolls when released, means for normally holding such padded means out of action, and power driven means for releasing the last named means and the padded means adapted to operate by the action of the rocking member.
5. In a spinning frame having front drawing rolls, a bobbin, and separable back drawing rolls, the combination of a rocking member, the front part terminating in a 75 thread guide over the bobbin between the front drawing rolls and the bobbin pivoted to rock on the frame, with padded means adapted to separate the back drawing rolls when released, means for normally holding 80 such padded means out of action, and power driven means for releasing the last named means and the padded means adapted to operate by the action of the rocking member.
6. In a spinning frame having front drawing rolls and a bobbin, together with back drawing rolls, one of which is positively driven and the other spring-pressed against it, the combination of a rocking member, the front part terminating in a thread guide located over the bobbin between the front drawing 85 rolls and the bobbin so arranged that the roving will be given a double bend in passing therethrough and being pivoted to rock on the frame, with padded means adapted to separate the back drawing rolls, and mechanism 90 operative by the rocking member together with spring mechanism releasable by such power means when operated by the rocking member to return the rocking member to its normal position.
7. In a spinning frame having front drawing rolls, a bobbin, and separable back drawing rolls, the combination of a rocking member, the front part terminating in a thread guide over the bobbin between the front drawing rolls and the bobbin pivoted to rock on the frame, with padded means adapted 95 to separate the back drawing rolls when released, means for normally holding such padded means out of action, and means for releasing the last named means and the padded means adapted to operate by the 100 action of the rocking member.
8. In a spinning machine having front drawing rolls and a bobbin, the combination 105

tion of a rocking member at one end of which is a thread guide through which the roving passes so located that the roving, in passing from the front drawing rolls to the 5 bobbin, will be given a double bend out of a straight course sufficiently to depress such eye and rocking member when the roving is being wound or spun on the bobbin, together with mechanism operative by the 10 rocking member adapted to stop the delivery of roving when an end breaks.

9. In a spinning frame, a rocking member, the front part of which terminates in a thread guide between the front drawing 15 rolls and the bobbin so arranged that the roving will be given a double bend in passing therethrough.

10. In a spinning frame having a positively driven bottom back drawing roll and a top back drawing roll driven therefrom 20 which can be moved out of engagement therewith, a padded lifting member normally held out of action and out of contact with both the top and bottom back drawing rolls, adapted when released to move the 25 top back drawing roll away from the bottom back drawing roll without coming in contact with said bottom back drawing roll and to stop said top back drawing roll from revolving.

In testimony whereof I have affixed my signature.

GEORGE M. ARRAGG.
